(57) **CLAIM**

The ornamental design for a solar powered light, as shown.

DESCRIPTION

FIG. 1 is a perspective view of a solar powered light embodying my design.

FIG. 2 is a front side elevational view thereof.

FIG. 3 is a right side elevational view thereof.

FIG. 4 is a rear side elevational view thereof.

FIG. 5 is a top plan view thereof; and,

FIG. 6 is a bottom plan view thereof.

The broken lines shown on the drawings depict portions of the solar powered light that form no part of the claimed design.
